United States Patent Office

Des. 231,373
Patented Apr. 16, 1974

231,373

GOLF CLUB HEAD

Richard Pavelle, Tucson, Ariz.
(3 Fieldstone Drive, Woburn, Mass. 01801)

Filed Mar. 3, 1972, Ser. No. 231,787

Term of patent 14 years

Int. Cl. D21—02

U.S. Cl. D34—5 GH

FIG. 1

FIG. 2

FIG. 3

FIG. 4

FIG. 1 is a top plan view of a golf club head showing my new design;

FIG. 2 is a side elevational view thereof;

FIG. 3 is a front elevational view thereof;

FIG. 4 is a rear elevational view thereof.

I claim:

The ornamental design for a golf club head, substantially as shown and described.
